UNITED STATES PATENT OFFICE.

EDMUND S. WHITAKER AND JOHN CHADWICK, OF PROVIDENCE, RHODE ISLAND.

SPINNING AND TWISTING MACHINE SPINDLE.

SPECIFICATION forming part of Letters Patent No. 593,448, dated November 9, 1897.

Application filed November 6, 1896. Serial No. 611,210. (No model.)

To all whom it may concern:

Be it known that we, EDMUND S. WHITAKER and JOHN CHADWICK, of the city of Providence, in the county of Providence and State 5 of Rhode Island, have invented certain new and useful Improvements in Spinning and Twisting Machine Spindles; and we hereby declare that the following is a full, clear, and exact description of the same, reference being 10 had to the accompanying drawings, forming part of this specification.

This invention has reference to an improvement in the bobbin-support for cap-spinning machines in which the spindle is stationary 15 and the bobbin-support rotates around the spindle.

The invention consists in the peculiar and novel construction of the bobbin-support and driving-whirl, whereby the same are supported by ball-bearings on a bolster secured 20 to the reciprocating rail above and below the driving-band, as will be more fully set forth hereinafter.

In cap-spinning machines as heretofore 25 constructed the bobbin-supporting tube and the driving pulley or whirl have usually been constructed to rotate and bear on the dead-spindle. As the bobbin has to be moved up and down to lay the yarn, the bobbin-tube, as 30 well as the whirl, must therefore move up and down on the spindle, and it becomes difficult to secure the perfect lubrication of the bearing of the tube on the spindle without throwing some of the oil outward from the 35 upper end of the tube as the bobbin is moved upward.

The object of this invention is to secure the desired steadiness of the rotating bobbin without contact between the supporting-tube 40 and the spindle.

Figure 1 is a side view of the improved bobbin-support for cap-spinning machines. Fig. 2 is a vertical sectional view of the same, indicating in broken lines one method for securing 45 the bolster to the rail.

In the drawings, 3 indicates the dead-spindle, to the upper end of which the usual cap is secured; 4, the reciprocating bolster-rail.

The bolster 5 is provided with a wide base 6, 50 of a diameter greater than the diameter of

the driving-pulley. The base is secured to the rail 4 firmly, so as to move with the same and form a firm support for the rotating bobbin-carrier. The base 6 is provided with pins or equivalent means and may be secured 55 by a nut engaging with a tube extending from the base through the rail, as is indicated in broken lines in Fig. 2, or other equivalent means. The race-ring 7 is placed or formed in the cup-shaped base 6. The upper end of 60 the bolster 5 is screw-threaded to receive the race-disk 8, internally screw-threaded. It can be therefore adjusted on the bolster 5, and when adjusted firmly secured by the lock-nut 9. 65

The bolster 5 is tubular and fits the spindle 3 with a loose sliding fit. The driving pulley or whirl 10 does not bear on the bolster 5, but is provided above and below the band-pull with cones and ball-bearings. At the 70 lower end the cup 11, of larger diameter than the diameter of the base 6, extends over and surrounds the base. It is provided with the race-ring 13, which, with the race 7 and the series of balls 15, forms the lower bearing of 75 the band-pulley 10, the upper end of which has the cup 12, of larger diameter than the band-pulley. The cup 12 is provided with the race-ring 14, which, with the race-disk 8 and the series of balls 15, forms the upper 80 bearing of the band-pulley 10. To secure perfect steadiness, all the points of contact on the balls are made of greater diameter than the bearing-surface of the band-pulley 85 or whirl.

The race-rings may be formed in the cups, but in practice we prefer to make them separate and force them into the cups. The upper part of the cup 12 is secured to the bobbin-base 16 preferably by screw-thread engagement. The base 16 is provided with the oil-inlet 17. The tube 18 extends upward from the base 16, to which it is secured, and the tube rotates with the base 16 and band-pulley 10. The bobbin rests on the base 16 95 and is supported by the tube 18 in the manner usual with cap-spinning machines. The interior of the tube 18 is not in contact with the spindle 3 and requires no lubrication. The bolster-tube 5 requires but little lubri- 100

cation. No oil is lifted up by the upper end of the tube 18 and none is thrown off on the interior of the cap or on the bobbin.

Having thus described our invention, we claim as new and desire to secure by Letters Patent—

1. In a cap-spinning-machine spindle, the combination with the dead-spindle, of a bolster-tube provided with a base adapted to be rigidly secured to the reciprocating rail, ball-races secured to and supported by the bolster-tube and its base, a band-pulley provided with enlargements above and below the band, ball-bearings of larger diameter than the band-pulley, and a bobbin-support connected with the upper enlargement of the band-pulley unsupported by the spindle, whereby the bobbin is rotated and supported against lateral vibration, as described.

2. In a spindle for cap-spinning machines, the combination with the dead-spindle 3, the bolster-rail 4, and the bolster 5 in sliding contact with the spindle, of a bobbin-support consisting of the whirl 10, the enlarged ends 11 and 12 of the whirl, ball-bearings within the enlarged ends of greater diameter than the whirl, the base 16 secured to the enlarged end 12, and the tube 18, the said bobbin-support revolv-

ing around the bolster-tube 5 and the dead-spindle 3 but not in contact with the same, whereby the bobbin is supported above the band-pull on bearings of larger diameter than the driving-surface of the whirl, as described.

3. In a spindle for cap-spinning machines, the combination with the dead-spindle 3 and the bolster-rail 4, of the bolster 5 in sliding contact with the spindle, the cup 6 supported on the bolster-rail and forming the base-support for the bolster-tube, the race 7 in the cup 6, and the race-disk 8 adjustably secured to the bolster-tube forming the stationary races for the ball-bearings, and a bobbin-support consisting of the tube 18, the base 16, the driving-whirl 10, the enlarged ends 11 and 12, the races 13 and 14, and the balls 15, 45 said bobbin-support revolving but not in contact with the bolster-tube and spindle, whereby the bobbin is rotated and supported against lateral vibration, as described.

In witness whereof we have hereunto set our hands.

EDMUND S. WHITAKER.
JOHN CHADWICK.
